SELF-LOCKING PUSH-BUTTON TUNING
MECHANISMMarion J. Pifer, Williamsville, N. Y., assignor to
Colonial Radio Corporation, Buffalo, N. Y.

Application November 14, 1947, Serial No. 785,925

6 Claims. (Cl. 74—10.33)

1

This invention relates to a push button tuning mechanism for radio receivers, and more particularly to a self locking cam mechanism for rocker and tilt bar apparatus.

In the commonly used rocker and tilt bar mechanism, the rocker or cam is adjustably mounted on a plunger, and locked in the desired position by a plate which clamps the cam so that the cam is held by friction. The clamping plate is ordinarily wedged in position by means of a threaded rod, which is sometimes rotated by rotation of the push button, in case the push button is round, but by a screw driver, in case the push button is square. In the latter instance, to make an adjustment of the cam such as is required in setting the push button to a new position, it is necessary for the user to remove the button and procure a screw driver or other tool, loosen the locking screw, reset the cam, tighten the locking screw, and replace the button.

It is an object of this invention to provide a mechanism in which no tools are required to reset the buttons, no clamping mechanism is employed, adjustments are greatly simplified, particularly where square push buttons are employed, and yet no parts of high precision, and consequently high cost, are employed.

It is a further object of this invention to provide such mechanism which is capable of high repeat accuracy of tuning, and is incapable of being accidentally jarred or knocked out of adjustment.

It is a further object of this invention to provide a mechanism of the class described which may be completely fabricated from screw machine and punch press parts, and which may be easily and quickly assembled with a minimum of expense.

Still other objects and advantages of my invention will be apparent from the specification.

The features of novelty which I believe to be characteristic of my invention are set forth in the appended claims. My invention itself, however, both as to its fundamental principles and as to its particular embodiments, will best be understood by reference to the specification and accompanying drawing, in which

Figure 1 is a top plan view of the tuner in accordance with my invention, partly broken away,

Figure 2 is a sectional view thereof on line 2—2 of Figure 1,

Figure 3 is a view similar to Figure 2, but showing the mechanism in position for resetting a push button,

Figure 4 is a section on line 4—4 of Figure 2, and

Figure 5 is a detailed section of a modified form of cam.

2

The tuner mechanism is mounted in a frame which may be a stamping having a front plate 10, a bottom portion 11, and end portion 12 and 13. Suitably secured to the front plate 10 at its upper portion, I am providing a bracket 14, provided with openings 15, 16, and 17, to accommodate the push buttons employed, and registering openings may be provided in the front plate 10. In the present embodiment, I have illustrated only three push buttons for the sake of simplicity, but it will be understood that as many may be provided as desired. The buttons in this instance are indicated as 18, 19, and 20, and operate sliders or plungers 21, 22, and 23.

In the present example of my invention, I have shown the tuner as operating permeability tuning cores 24, 25, and 26, attached to a carrier 27, and adapted to be moved longitudinally by tilt bar assembly 28. It will be understood, however, that my invention may equally well be applied to operate other types of tuning mechanism such as variable condensers.

The tilt bar assembly may comprise upper and lower bars 29 and 30, mounted in end plates 31 and 32, which in turn are mounted in bearings 33 and 34 in the end plates 12 and 13. As will be understood, the tilt bar assembly oscillates in the bearings 33 and 34, and the extended end plates 31 and 32 engage the core carrier 27 so as to move the cores 24, 25, and 26 longitudinally as the tilt bar oscillates.

In the embodiment of the invention now described, the stopping position of the tilt bar assembly 28 is determined by cams 35, 36, and 37 for the respective push buttons 18, 19, and 20. Each of these cams in the embodiment now described may comprise a wedge shaped stamping of strip metal having registering screw threaded openings at the base of the wedge. Each cam is mounted on a threaded rod, the rods being 40, 41, and 42 respectively, and each rod has near its upper extremity a smaller unthreaded portion 43 (Figure 2), and each is provided at its lower extremity with a ball 44 resting in a socket 45 and with a projecting smaller end portion 46 extending through a clearance opening in the socket 45. This permits the rods 40, 41, and 42 to tilt from the full line or operating position in Figure 2, to the dotted line or unused position.

It will be seen that by rotation of the rods 40, 41, and 42, their respective cams 35, 36, and 37 may be raised or lowered, and the position of these cams determines the stopping position of tilt bar assembly 28. Each of the push button plungers 31, 32, and 33 has a forked end portion 50, 51, and 52, respectively, which engages the unthreaded portion of the threaded rods 40, 41, and 42 to tilt them from the position shown in

the dotted lines in Figure 2, to the full line position.

How the various cams may be adjusted by rotation of the rods on which they are mounted will now be described.

A manual adjusting shaft 55 carrying knob 56 is mounted in brackets 57 on a bail 58 pivotally mounted on bearings 59 and 60 for slight rocking movement. The shaft 55 carries near its extremity a worm 61 engaging gear 62 secured to shaft 63, mounted in bearings 64 and 65 in the bail 58 and passing through clearance openings in end plates 11 and 12.

The shaft 63 is threaded for engagement with gears 67, 68, and 69 secured on threaded rods 40, 41, and 42, respectively. Bail 58 may be spring biased to the position shown in Figure 3 by spring 70 secured to extensions 71 and 72 of the bail and to the frame end plates 11 and 12. The dimensions are so related that when a push button is depressed, as in Figure 2, engagement between threaded shaft 66 and gears 67, 68, and 69 still is not made. Engagement is made between any depressed push button, gear 67, 68, or 69 and the shaft 66 only when the manual adjusting knob 56 is pushed downwardly, swinging the bail counterclockwise from the position shown in Figure 2 to the position shown in Figure 3. When this occurs, gear 67, 68, or 69, as the case may be, is engaged by shaft 66, and rotation of knob 56 will cause rotation of shaft 63, in turn rotating the respective rod 40, 41, or 42, and moving the respective cam 35, 36, or 37 upward or downward. This in turn will cause partial rotation of the tilt bar assembly 28 to change the tuning of the receiver.

Therefore, to set up a station, all that is necessary is to push in the desired button, push down knob 56, and rotate it until the desired station, for which the button is to be set, is tuned in. When the knob 56 is released, its spring bias returns it to the position shown in Figure 2, disengaging shaft 63 from the respective gear 67, 68, or 69. Repeated operation of any or all of the push buttons, therefore, can not cause accidental movement of the cams from the preset position, because shaft 63 never engages the adjusting gears 67, 68, and 69 unless the knob is pushed down to the position shown in Figure 3.

Cams 35, 36, and 37 may take various forms. For instance, instead of the wedge shape shown in Figure 3, the cam may be in the form of an inverted wedge, or M, as at 75 in Figure 5, and in any case, it may be desirable to extend one end of the cam to project through a clearance opening in the front plate 10. Springs 80 may be provided in each push button to bias the same to outward position, the spring being attached on one end to the respective cam and to a suitable opening in the frame.

While I have shown and described certain preferred embodiments of my invention, it will be understood that modifications and changes may be made without departing from the spirit and scope thereof, as will be clear to those skilled in the art.

In the specification I have explained the principles of my invention and the best mode in which I have contemplated applying those principles, so as to distinguish my invention from other inventions, and I have particularly pointed out and distinctly claimed the part, improvement, or combination which I claim as my invention or discovery.

I claim:

1. In a push button tuner, in combination, a frame, a plurality of plungers mounted in said frame, a plurality of tilttable levers pivotally mounted in said frame for rocking motion when actuated by said plungers respectively, cams adjustably positioned on said levers and movable longitudinally thereof, means for moving said cams longitudinally of said levers, and a tilt bar mounted in said frame for rocking motion, and for engagement with said cams.

2. In a push button tuner, in combination, a frame, a plurality of plungers mounted in said frame, a plurality of tilttable levers pivotally mounted in said frame for rocking motion when actuated by said plungers respectively, cams adjustably positioned on said levers and individually movable longitudinally thereof, means extending out of said frame for moving said cams longitudinally of said levers, and a tilt bar mounted in said frame for rocking motion and for engagement with said cams.

3. In a push button tuner, in combination, a frame, a plurality of plungers mounted in said frame, a plurality of tilttable levers pivotally mounted in said frame for rocking motion when actuated by said plungers respectively, cams adjustably positioned on said levers and individually movable longitudinally thereof, a bail pivotally mounted on said frame, a shaft connected thereto extending beyond said frame, said first shaft being movable into and out of engagement with said levers, and means for causing rotation of said second shaft to move said cams longitudinally of said levers.

4. In a push button tuner, in combination, a frame, a plurality of plungers mounted in said frame, a plurality of levers mounted in said frame for rocking motion when engaged by said plungers respectively, cams adjustably mounted on said levers and individually movable longitudinally thereof, means selectively engageable with any one of said levers to effect longitudinal adjustment of said cams, and a tilt bar engageable and movable to a predetermined position by each of said cams.

5. In a push button tuner, in combination, a frame, a plurality of plungers mounted in said frame, a plurality of levers mounted in said frame for rocking motion when engaged by said plungers respectively, cams screw-threadedly mounted on said levers and individually movable longitudinally thereof by rotation of said levers, gears mounted on said levers, a worm selectively engageable with said gears for rotating said levers to adjust said cams longitudinally of said levers, and a tilt bar engageable and movable to a predetermined position by each of said cams.

6. In a push button tuner, in combination, a frame, a plurality of plungers mounted in said frame, a plurality of levers mounted in said frame for rocking motion when engaged by said plungers respectively, cams screw-threadedly mounted on said levers and individually adjustable longitudinally thereof by rotation of said levers, gears mounted on said levers, a transversely movable worm movable into and out of engagement with said gears, means for moving and rotating said worm, and a tilt bar engageable and movable to a predetermined position by each of said cams.

MARION J. PIFER.
